(57) **CLAIM**

The ornamental design for a surgical template for dental
implant, as shown and described.

DESCRIPTION

FIG. 1 is a bottom perspective view of a surgical template
for dental implant embodying my design;

FIG. 2 is a top perspective view thereof;

FIG. 3 is a top plan view thereof;

FIG. 4 is a right side elevational view thereof, the left side
elevational view being a mirror image of the right side
elevational view; and,

FIG. 5 is a front elevational view thereof, the rear elevational
view being a mirror image of the front elevational view.
